STEAM DRIER

Pasquale Pascale, New York, N. Y., assignor to
 Novo Patents, Inc., a corporation of Delaware

Application September 24, 1936, Serial No. 102,438

6 Claims. (Cl. 183—108)

This invention relates to improvements in devices for removing suspended or entrained moisture or condensate from steam or other gases and is especially adapted for use with the boilers of 5 locomotive, marine or stationary engines and similar devices wherein a drier is interposed between a source of steam supply, such as the steam chamber of an engine, and a point of use, such as a superheater or the cylinders of an engine.

10 Steam driers and similar devices as heretofore constructed have in many instances been limited in capacity due to the resistance to the passage of steam or gas therethrough presented by the drying means employed. In other constructions the 15 capacity is large and the resistance to flow of steam or gas through the device is small but these advantages are accompanied by a reduction in the effectiveness of the drier in removing moisture from the steam.

In accordance with the present invention disadvantages and objections to prior constructions 20 are overcome by the provision of novel drying means which effectively remove moisture from steam or gas without imposing material resistance to the flow of steam therethrough.

25 In the representative forms of the invention illustrated in the drawings and hereinafter more fully described, the means provided for denuding the steam or gas of moisture include baffle members against which the steam impinges and certain other baffle members are formed with apertures presenting a total cross sectional area that is relatively large and may, if desired, be equal to or greater than the cross sectional area of the 30 inlet or outlet opening so that steam or gas in passing through the device is not materially impeded. Further the baffle members employed may in some instances be so constructed and arranged that steam passing upwardly thereover impinges on a projecting and downwardly sloping surface which serves further to denude the steam or gas of moisture. These surfaces may also serve to conduct the moisture deposited thereon away from the upwardly flowing steam so as to avoid reentrainment of the moisture by the steam.

45 One of the objects of the present invention is to provide novel means for drying steam or other gases which are simple in construction and effective in operation.

50 Another object of the invention is to provide a drier which offers relatively small resistance to the passage of steam or other gases therethrough while effectively denuding the steam or gas of moisture.

55 A further object of the invention is to provide a

steam drier having means provided with apertures through which the steam passes, the total cross sectional area of which apertures is relatively great and may be substantially equal to the cross sectional area of the passage through which the 5 steam enters or leaves the drier.

A further object of the invention is to provide a steam drier having baffle members arranged therein and formed with projecting inclined surfaces positioned to cause steam passing upwardly 10 thereover to impinge thereon whereby the steam is denuded of suspended or entrained moisture.

Another object of the invention is to provide a steam drier with a baffle and means for conducting moisture deposited on the baffle out of the path of 15 flow of steam passing thereover.

These and other objects and features of the invention will appear from the following description thereof in which reference is made to the accompanying figures of the drawings wherein 20 typical embodiments of the invention are illustrated.

In the drawings:

Figure 1 is an elevation of a typical form of steam drier embodying the present invention with 25 parts thereof broken away to show the interior of the casing;

Figure 2 is a plan view of the construction illustrated in Figure 1 with parts broken away to show more clearly a suitable arrangement of the steam 30 drying elements.

Figure 3 is a view partly in elevation and partly in section of an alternative embodiment of the invention, and

Figure 4 is a plan view of the form of the invention shown in Figure 3 with the casing partly broken away to show the interior arrangement.

Referring to that form of the invention illustrated in Figures 1 and 2 of the drawings the numeral 1 designates a casing formed in the main 40 of a lower section 2, an upper section 3, and a dome or cover 4. Interposed between the sections 2 and 3, is a cage 5 which is suitably secured to the two sections and may be made up of numerous blades 6, spaced apart to form between them the 45 vertical steam inlet openings 7.

While the inlet opening or openings may be of any suitable form they are shown in Figure 2 in the form of vanes 6 so shaped in cross section and so arranged with relation to each other that the 50 steam passes into the casing in a direction substantially tangential to the axis of the casing, and the cage is made of arcuate or curved sections, the vanes in each alternate section being reversed with relation to those in the adjoining section, the 55

result being that the incoming currents of steam are brought into conflict with greater resultant agitation, and since the sections so arranged extend entirely around the casing, a balancing action results and is maintained.

The dome 4 has a laterally extending annular flange 8 which overlies the upper inner edge of the section 3 through which pass bolts 9 by which the dome is secured to said section. The lower section 2 is formed with an outer wall 10, an inner wall 11, and a bottom 12, connecting the walls and forming an annular drainage chamber 13, to which is connected the upper end of a drain pipe 14. A suitable check valve 14' is located in the drain pipe 14 for return of the condensate or separate from the steam to the boiler for reuse.

Integral with the inner wall of section 2 is a comparatively wide flange 15, extending entirely around the casing on the inside thereof, and forming an annulus for supporting perforated drying or baffling means of suitable form. As shown the annulus is provided with openings 16, which register with the lower opened ends of numerous cylindrical drier elements or baffle members 17, each of which is provided with a large number of perforations or nozzles 18. The upper open ends of these drying cylinders are seated in shouldered openings 19 in an annulus 20, integral with the dome 4. The shape and construction of the members 17 may be varied as desired but by providing such means with a suitably extended surface and with a sufficient number of apertures the total cross sectional area of the apertures provided for the passage of steam 35 may be relatively great and may be substantially equal to or greater than the cross sectional area of the outlet opening so that the resistance to the passage of steam through the device is decreased without impairing the effectiveness thereof. 40

Extending upwardly from the flange 15 is a central tubular portion 21, whose upper edge is seated in a shouldered recess 22 in the annulus 20, the upper end of the tubular portion 21 being open, thereby establishing connection between the dome and the interior portion of the casing. The dry pipe 23 through which dry steam or gas passes from the device is secured by bolts 24 to the downwardly extending flange 25 of a ring 50 26 which is securely bolted to the bottom of the casing.

Firmly bolted to the outer face of the flange 15 is a baffle 27 which as shown may be generally tubular in form and extend entirely around the casing, with its upper edge spaced below the upper ends of the drying cylinders, and its lower end somewhat above the floor of the annular chamber 13. The baffle 27 thus forms an outer annular passage through which the steam or gas 55 passes upwardly from the inlet openings 7 to the top of the casing and an adjacent inner passage within which the cylindrical perforated baffle members are located and through which the steam or gas passes downwardly and through the 60 perforations in the cylinders to the dry pipe 23.

The upper portion of the baffle 27 extends outwardly toward the inlet openings 7 presenting a projecting downwardly sloping surface 27a against which steam flowing upwardly over the 70 baffle member impinges so that moisture carried thereby will be deposited on the sloping surface 27a. This surface slopes inwardly away from the inlet openings so that moisture collecting thereon and running down the surface is carried 75 out of the path of flow of the upwardly pass-

ing steam. In this way the danger of reentrainment of moisture by the upwardly flowing steam is reduced and the effectiveness of the drying action of the baffle member is increased. Moreover, the inner surface of the baffle member 5 27 is similarly formed so that the distance between the baffle member 27 and the perforated cylinders 17 is less near the bottom of the cylinders causing the steam to be forced through the perforations in the cylinders as it flows downwardly thereover.

The flange 15 between the baffle 27 and the cylinders is provided with a number of openings 27' communicating with the drainage chamber, so that the water or moisture of which the steam 15 is denuded before passing through the perforations in the cylinder may pass into the drainage chamber 13 to mingle with that which has been drained from the steam in passing through the steam inlet openings, and impinging against the 20 outer face of the baffle. The condensate or separate from the steam or gas in both passages thus flows freely into the drainage chamber and to the drain pipe 14 to be returned to the boiler.

The dome 40 with which the upper ends of the 25 cylinders 17 communicate is shaped to form a chamber 28 semi-circular in cross section as shown, to direct the dried steam downwardly through the central portion 21, where it joins the dried steam issuing from the lower ends of the 30 drying cylinders on its way to the dry pipe. An eye-bolt such as is indicated by 28' is centrally mounted in the dome to facilitate handling the drier in installing it in the boiler, and in its removal therefrom.

It will be noted from the description of Figures 1 and 2, that there is within the casing, an annular chamber "A" formed by the circular baffle 27 and the wall "B" of the central tubular portion 21, the chamber being open at its top as indicated at "C" through which opening, the steam passes downwardly into said chamber and around all of the cylindrical perforated drying members. There is no communication through the upper ends of the drying cylinders except through 45 the annulus 20, consequently, as indicated, the steam passing into the open space between the baffle 27 and the cylinders can only pass into and through the central tubular opening 21, after passing through the perforations in the 50 cylinders. Thereafter it can pass from the cylinders upwardly into and through the dome and downwardly through the lower ends of the drying cylinders to the dry pipe.

Referring now to Figures 3 and 4 in which an 55 alternative form of drier is shown, the casing is in the main made of two sections, a lower section 29 and an upper section 30, between which is interposed a cage 31 having elongated circumferential inlet openings 32. In this form of the 60 invention the inlet openings are shown as formed between the circumferential vanes 33, the inner ends of which vanes are turned downward so as to conduct or direct the steam downward toward the center of the casing.

Spaced from the inner wall of the lower section 65 is a supporting ring 34, which rests upon a ledge 35 of the lower section 29. The inner edge of this ring extends upwardly and inwardly toward the center of the casing and is provided with a flange 70 for supporting the drying members or cylinders 38. These cylinders are located at spaced intervals about the flange and are suitably arranged to provide extended perforated surfaces. The lower ends of the cylinders 38 are closed except 75

for the relatively small drainage openings 39 which coincide with openings 37 in the supporting flange on ring 34 to permit the condensate or separate accumulating in the bottoms of the cylinders to pass to the annular drainage chamber 39'. This chamber, like the chamber 13, in Figure 1, extends entirely around the casing for the collection and removal of liquid removed from the steam or gas.

10 Secured to the under side of the dome or upper section 30 of the casing is an annular supporting ring 40 having shouldered seats therein, as indicated at 41, for the reception of the upper edges of the cylinders 38, which, like the cylinders 15 in the form of the invention illustrated in Figures 1 and 2, are provided with numerous perforations or nozzles 42. The upper ends of these cylinders are in communication with the annular chamber 43 in the dome. The outer edge of this supporting 20 ring is shouldered and flanged as indicated at 44 for the reception of the upper end of a baffle 45 which extends entirely around the casing with its lower end resting upon the ledge 35. Secured to the bottom of the casing is a ring 47 provided 25 with a flange 48, to which is attached the dry pipe 49 which communicates with the central chamber within the casing.

The arrangement of the outer wall of the lower section 29, and the inwardly inturned portion of 30 the supporting ring 34 is such that the drainage chamber 39' is formed. The lower end of the baffle bisects the drainage pipe 46, which is let into the bottom of the section 29, so that the condensate or separate will pass from both sides 35 of the baffle into the drainage pipe.

In operation, referring particularly to the form shown in Figures 1 and 2, the steam passes into the casing through spaces between the vanes of the cage from all sides of the casing simultaneously, and is conducted and directed in conflicting currents (caused by the indicated shape and arrangement of the vanes) against the circular baffle 27 and passes upwardly thereover depositing much of the moisture carried thereby on the surface 27a down which it drains out of the path of the upwardly passing steam. The steam then passes downwardly over the upper edge of the baffle 27 into the chamber formed between the wall of the central tubular portion 21 and the baffle 27. This chamber extends entirely around the casing and is closed at its lower end except for the drainage openings 27' and is of smaller diameter near the lower portion thereof so that steam or gasses being dried necessarily pass 50 through the numerous perforations or nozzles 18 in the cylindrical members 17 thereby being denuded of substantially all of the remaining moisture carried thereby. Both ends of the drying cylinders are open so that the resulting dry steam may pass from the upper ends thereof through the chamber 28 in the dome, into the central tubular portion 21, to the dry pipe whereas dry steam from the lower ends of the drying cylinders passes directly to the dry pipe. 55 In this way the steam is dried or denuded of moisture very effectively while the resistance to flow of steam through the drier is very low.

In the form of the invention shown in Figures 3 and 4 the course of the steam, in passing through 60 the drier, is somewhat different from its course in passing through the apparatus of Figures 1 and 2. In the modified form, the steam passing, through the circumferential inlets in the casing wall impinges against the baffle 45, but it cannot 65 reach the open upper ends of the drying cylinders

38, save through the dome of the casing, and from thence the dried steam passes through the nozzle or perforations 42 in all radial directions to the dry pipe. The condensate passes through the openings in the closed ends of the cylinders and is led into the drainage chamber.

In each of the forms of the invention illustrated and described it will be noted that the perforated cylindrical members present extended surfaces and are provided with a multitude of apertures so that the total cross sectional area of the apertures in the members 17 and 38 is relatively large and may if desired, equal or exceed the cross sectional area of the inlet or outlet openings so that the resistance to the passage of steam through the device is relatively low. At the same time the drying action of the baffle members is not impaired since the steam must pass through apertures which are individually relatively small.

While the perforated members illustrated in the drawings are cylindrical in form it will be apparent that such members may be of any other suitable shape or construction and the arrangement thereof within the casing may be altered as desired or necessary to adapt the invention for use in any particular installation. In view thereof it should be understood that those forms of the invention herein illustrated and described are intended to be illustrative of typical embodiments of the invention and are not intended to limit the scope thereof.

I claim:

1. A steam drier including a casing having steam inlet and outlet openings, a plurality of vertically extending hollow steam drying elements open at their upper and lower ends and provided with perforations in the walls thereof, said steam drying elements communicating with said outlet opening only through the openings in the top and bottom thereof, whereby the steam in passing from said inlet to said outlet opening must pass through the perforations in said drying elements before reaching the outlet opening.

2. A steam drier including a casing having numerous elongated steam inlet openings in a wall portion thereof, a plurality of vertically extending hollow steam drying elements open at their upper and lower ends and provided with perforations in the walls thereof, said steam drying elements communicating with the outlet opening only through the openings in the top and bottom thereof, so that the steam in passing through said elements must pass through the perforations therein before reaching the outlet opening, and a baffle interposed between the steam inlet openings and the drier elements against which the steam impinges before reaching said elements, and means for conducting the condensate or separate from the steam out of said casing.

3. A steam drier including a casing having steam inlet openings circumferentially arranged in a side wall portion, an outlet opening, an interior structure including an annular chamber, means establishing communication between said annular chamber and the inlet openings for admission of steam to said chamber, a plurality of drying elements located in said annular chamber and provided with numerous perforations for the passage of steam therethrough, said drying elements being open at their upper and lower ends for the passage of dried steam to the outlet opening, only after it has passed through said perforations.

4. A steam drier including a casing having steam inlet openings circumferentially arranged in a side wall portion, an outlet opening, an interior structure including an annular chamber, means establishing communication between said annular chamber and the inlet openings for admission of steam to said chamber, a plurality of hollow drying elements located in said annular chamber and provided with numerous perforations for the passage of steam therethrough, each of said drying elements being provided with an opening for the passage of dried steam from the interior thereof to the outlet opening only after it has passed through said perforations.
5. A steam drier including a casing having numerous steam inlet openings arranged in a wall portion thereof and an outlet opening for dried steam from the casing, means defining an annular chamber within said casing, said annular chamber being in communication with said inlet openings, a plurality of hollow drying elements located in said annular chamber and provided with numerous perforations for the passage of steam therethrough, each of said drying ele-

ments being provided with an opening for the passage of dried steam from the interior thereof to the outlet opening only after it has passed through said perforations.

6. A steam drier including a casing having numerous steam inlet openings arranged in a wall portion thereof and an outlet opening for dried steam from the casing, means defining an annular chamber within said casing, said annular chamber being in communication with said inlet openings, a plurality of hollow drying elements located in said annular chamber, said elements being provided with numerous perforations in their side walls and forming extended steam drying surfaces, each of said drying elements being further provided with an opening to permit substantially unrestricted flow of steam between the interior of the element and an adjacent passage, and said elements being so positioned between said inlet openings and said outlet opening that the steam in passing through said elements must pass through the perforations therein before reaching the outlet opening.

PASQUALE PASCALE.
